FOREST G. GAUNTT, OF FORT WAYNE, INDIANA.

FEEDING MECHANISM.

Specification of Letters Patent. Patented June 23, 1914.

1,101,174.

Application filed February 10, 1913. Serial No. 747,227.

To all whom it may concern:

Be it known that I, FOREST G. GAUNTT, a citizen of the United States, residing at Fort Wayne, Allen county, Indiana, have invented new and useful Feeding Mechanisms, of which the following is a specification.

This invention relates to handling material at regular and uniform rates and to the driving devices therefor.

This invention has utility when embodied in feeding mechanisms, especially for handling small grain, or powdered material, in the handling of which the scroll conveyer 15 adaptation has special value.

Referring to the drawings Figure 1 is a longitudinal section of a scroll conveyer embodiment of the invention in a feeding mechanism; Fig. 2 is a view in elevation 20 from the right of Fig. 1; and Fig. 3 is a section on the line III—III of Fig. 1, looking in the direction of the arrow.

The drive wheel 1 may be actuated from any source of power to rotate the shaft 2 25 mounted in the bracket 3 on the side of the hopper 4; and in the bracket 5 mounted on the opposite end of the housing 6. The end of the shaft 2 remote from the drive wheel 1, has the crank 7 connected by the hook 30 link 8 to the rock lever 9 having the adjustable fulcrum block 10, movable by the hand wheel 11 to shift the block 10 along the slot 12 in the lever 9. The fulcrum block 10 is pivotally mounted in the bracket 35 13 extending from the housing 6 adjacent the bracket 5. Links 14, 15, pivotally connected to the lower end of the rock lever 9, extend to the arms 16, 17 loosely mounted on the shaft 18 extending longitudinally 40 through the housing 6. The arm 17 carries a pawl 19 falling by gravity to engage the ratchet wheel 20 mounted on the shaft 18. The arm 16 carries a pawl 21 having a counterweight 22 at its lower end to keep it 45 swung into engagement with the ratchet wheel 20. This variable speed intermittent grip device may effect such slow or reduced speed of continuous rotation as may be desired for the shaft 18. The housing 6 has 50 the intake or hopper opening 4 adjacent the drive wheel 1, while adjacent its other end, the housing 6 has the discharge or outlet opening 23. The housing 6 has the semi-cylindrical bottom 24 throughout its length.

Disposed in the housing 6 adjacent the 55 downwardly tapering intake opening 4, is the upper semicircular or semicylindrical member 25 to complete a stroke measuring section of the housing 6 adjacent the intake opening 4. To effect stroke measuring, the 60 double pitch rotary scroll supply conveyer 26 leads from the hopper or intake opening 4 into the circular opening provided by the bottom 24 and the member 25. The rotation of this supply conveyer 26 may be at 65 such adjusted feed rate for the material to be handled as may be desired. When driven at a slow rate, some kinds of small particle materials tend to clog and fall forward in lumps, causing the delivery from the feed- 70 mechanism conveyer 26 not to be uniform. To overcome this difficulty, there is mounted on the shaft 18 in alinement with the conveyer 26, and in the housing 6, the sleeve 27, carrying the brackets 28 sustain- 75 ing the ribbon scroll conveyer 29. By tapering the hopper 4 to widen downwardly as shown in Fig. 1 there is more freedom for fall of the material. This second conveyer is driven by the sprocket wheel 30 on the 80 sleeve 27. The sprocket wheel 30 is actuated by the sprocket chain 31 extending from the sprocket wheel 32 on the shaft 2 adjacent the bracket 5. With the intermittent grip speed reduction device driving the primary 85 or less capacity conveyer 26, at a reduced speed rate, the direct high speed drive of the secondary beater or ribbon scroll conveyer 29, gives this second conveyer a greater capacity than the conveyer 26, and 90 due to its higher speed operation it is continually making hold of the material from the conveyer 26 in small quantities and quickly beating it up for uniform discharge in a subdivided state at the opening 23. Con- 95 veyer 29 is accordingly an equalizer. The feeding mechanism as above disclosed accordingly possesses exceptional utility for feeding at definite rates, especially in mixing materials, as feed, flour, etc. The hook 100 on the link 8 permits ready cutting out of the feed at any time, being of special value in times of emergency. The ribbon conveyer 29 allows a falling back in the openings between it and the shaft of large quantities of 105 the material instead of pushing the lumps forward, so that in its operation it effects a constant feed in a regular stream. The

partition 33 in the housing 6 prevents the material from clogging the sprocket chain drive for the ribbon 29.

What is claimed and it is desired to secure 5 by Letters Patent is:

1. A feeding mechanism comprising a housing provided with an intake opening and a discharge opening, a first rotary scroll conveyer to effect stroke measuring in the 10 intake opening of the material handled, positive driving means for the first conveyer, a second rotary similar diameter scroll conveyer adjacent the discharge opening and coaxial with the first conveyer to effect uniform 15 discharge of the material handled, and higher speed driving means for the second conveyer operative during the driving of the first conveyer.
2. A feeding mechanism comprising a 20 housing provided with intake and discharge openings, a first scroll conveyer in the housing adjacent the intake opening, an increased angular velocity similar diameter scroll conveyer in the housing adjacent the 25 discharge opening and in alinement with the first scroll conveyer and driving means continuously actuating said scroll conveyers.
3. The combination of a pair of coaxial scroll conveyers of common diameter and 30 different capacities, the lesser capacity being disposed to deliver to the greater capacity, positive driving means for the lesser capacity conveyer and additional continuous driving means for the greater capacity conveyer.
4. The combination of a plurality of 35 aligned conveyers of common diameter and different capacities, a lesser capacity conveyer being disposed to deliver to a greater capacity conveyer, positive driving means for the lesser capacity conveyer, and additional continuous driving means for the greater capacity conveyer.
5. A feeding mechanism comprising a 40 supply conveyer, in alinement therewith a ribbon beater of similar radial extent as the supply conveyer to which said conveyer delivers, driving means for the beater, and less rate driving means for the supply conveyer, said beater having axially disposed shaft, 45 arms radiating therefrom and a scroll ribbon carried by the arms whereby the dis-

charge from the supply conveyer may be subdivided for continuous uniform delivery by the beater.

6. A feeding mechanism comprising a supply conveyer, a beater of similar radial extent as the supply conveyer in alinement therewith and to which said conveyer delivers, driving means for the beater, and less speed driving means for the conveyer. 55

7. A feeding mechanism comprising a supply conveyer, a ribbon beater coaxial with said conveyer to which said conveyer may deliver, a positive driving device for the conveyer independent of the operation of the beater, a cut out for the driving device whereby the supply to the beater may be changed, and driving means for the beater independently of the driving device for the conveyer whereby the beater may agitate 70 and handle the entire delivered quantity from the conveyer even after the cut out has become effective.

8. A feeding mechanism comprising a supply conveyer provided with a shaft, a material agitating beater mounted on the conveyer shaft, driving means for the conveyer independent of the operation of the beater, a cut out for the conveyer whereby the supply to the beater may be changed, and driving means for the beater whereby the beater 75 may agitate and handle the entire delivered quantity from the conveyer even after the cut out has become effective.

9. A feeding mechanism comprising a supply conveyer having a shaft, a beater to which said conveyer delivers which beater is sleeved upon said conveyer shaft, adjustable driving means for varying the speed or cutting out the conveyer whereby the supply to the beater may be changed, and driving means for the beater whereby the beater may handle the entire delivered quantity from the conveyer even after the cut out has become effective. 80

In testimony whereof I affix my signature in the presence of two witnesses.
